UNITED STATES PATENT OFFICE.

CHARLES F. CALLAHAN, OF MEMPHIS, TENNESSEE.

REFRIGERATING VENDING MACHINE.

Application filed February 12, 1923. Serial No. 618,630.

To all whom it may concern:

Be it known that I, CHARLES F. CALLAHAN, a citizen of the United States, residing at Memphis, in the county of Shelby and State 5 of Tennessee, have invented certain new and useful Improvements in Refrigerating Vending Machines; and I do hereby declare the following to be a full, clear, and exact description of the invention, such as will enable others skilled in the art to which it 10 pertains to make and use the same.

The present invention relates to improvements in refrigerator vending machines, and has for an object to provide a refrigerator for containing bottled goods in which the delivery of the goods is had without requiring the opening of the refrigerator to the end that the goods may be at all times kept at a constant low temperature suitable 20 for drinking purposes and to avoid the expense of wasted refrigerant when the cold is allowed to escape through the opening of doors to give access to the contents of the refrigerator.

It is another object of the invention to provide in conjunction with the refrigerator a coin-controlled apparatus to regulate the delivery of the goods so that the device is substantially automatic in action, and provides for the vending of the articles singly 30 only after the deposit of a coin of predetermined denomination in the apparatus.

Further objects of the invention are to provide for a compact refrigerator having 35 numerous compartments in which several varieties of different goods may be stored from which the customer may make his selection, to provide a relatively simple and inexpensive construction of both refrigerator and coin-controlled apparatus and to provide for a ready and convenient delivery of the goods to the exterior of the refrigerator upon the actuation of the respective coin-controlled apparatus.

With the foregoing and other objects in view, the invention will be more fully described hereinafter, and will be more particularly pointed out in the claims appended hereto.

In the drawings, wherein like symbols refer to like corresponding parts throughout the several views,

Fig. 1. is a front elevation of an improved vending refrigerator constructed according 55 to the present invention.

Fig. 2. is a vertical sectional view thereof.

Fig. 3. is a fragmentary horizontal section.

Fig. 4. is a fragmentary vertical section showing the delivery apparatus. 60

Fig. 5. is an enlarged fragmentary section through the coin controlled mechanism, and

Fig. 6. is also a section taken on the line 6-6 in Fig. 5. 65

Referring more particularly to the drawings 1 designates a cabinet or chest adapted to contain ice in a top compartment 2 and having double spaced walls as indicated at 3 to properly insulate the interior. 70

The ice or other refrigerant in compartment 2 at the top of the cabinet or chest is accessible for filling through one or more doors 4 also preferably of a double wall construction having an interior dead air or other insulated space. Below the refrigerant compartment 2 are a number of intermediate compartments placed side by side throughout the width of the cabinet or chest and serving to hold bottled goods of various kinds. These compartments are indicated generally at 5 in Fig. 2, and are provided with inclined shelves 6, 7, 8 and 9 upon which bottles are laid sidewise to enable them to roll. The bottles are put in through two spaced hinged doors 10 and 11 which swing inwardly as the bottle is pushed into place. These doors 10 and 11 are separated substantially the width of the bottle 80 to enable the outermost door 10 to close before the bottle will in its rolling automatically open the inner door 11; thus preventing the escape of the cold atmosphere. 85

The doors 10 and 11 are situated above the glass panels 12 through which the prospective customer may view the contents of the various intermediate compartments. As shown in Fig. 1 six compartments are provided in which various bottled goods are carried as indicated by the legends above 90 the glass panels. The base 13 of the opening through which the bottles are introduced extends on the same inclination as the topmost shelf 6. This shelf slopes rearwardly but is spaced from the rear wall of the cabinet as shown in the Fig. 2 to permit the bottles to descend upon the higher end of the next shelf 7 which is inclined forwardly and in turn has its front end spaced from the front part of the refrigerator to 100 again allow the goods to descend upon the shelf 8, which is next in sequence.

105

110

The shelf 8 assumes an inclination similar to the top shelf 6 and directs the bottles upon the lowermost shelf 9 which is similar in position to the second shelf 7. The shelves are reinforced and the bottles guided by braces 14 which act as roofs for the zig-zag path taken by the bottles. The arrangement is such that the ice in the top compartment 2 may melt and the cold water descend upon the bottles 15 in the intermediate compartments, finally descending upon the sloping floor 16 which is inclined to the drain pipe 17. Below the bottom 16 is a compartment 18 for such other goods as it may be desired to keep in the refrigerator. For instance bottled goods may be kept in suitably large quantities in the base compartment 18 and an attendant making his rounds of the various machines may have resort to this base compartment for goods to replenish any of the intermediate delivery compartments which may at the time be empty.

Now each of the intermediate compartments is provided with a coin-controlled mechanism embodied in a casing 19 and operated by lever 20 which is connected by rod 21 with a slide 22 operating beneath the outlet from the lowermost shelf 9 and having a pocket 23 to receive a single bottle while also having an upper flange 24 to close the mouth at the lower end of shelf 9 when the slide moves to an outer position such as shown in Fig. 4. The front wall of the cabinet provides a chute 25 into which the bottle is delivered when the slide 22 is pulled forwardly, the bottle being directed outwardly to a basket or holder 26 which is upon the exterior of the cabinet and accessible to the customer. A hinged door 27 is located in the chute or at its outlet to be swung open by the bottle in its passage to the basket but adapted to automatically close to avoid dissipation of the cold atmosphere.

The coin-controlled mechanism is shown most clearly in Figs. 5 and 6 in which the casing 19 is shown to be provided with an opening 28 to receive a coin of suitable denomination which is adapted to descend by gravity into the slot 29, the coin 30 being shown in Fig. 6, as having just descended and come into contact with the upper end of a lever 31 which normally projects into the lower portion of the slot 29. The lever 31 is fulcrumed at 32 and has its lower end 33 normally projecting in the path of a lug 34 upon a rotary shaft 35 which projects through one side of the casing 19 to which is affixed the lever 20.

A trip finger 36 extends beneath the coin 30 at the base of the coin slot 29 preventing the immediate descent of the coin, this finger being pivoted as indicated at 37 in Fig. 5 upon a suitable part and being connected

to a link 38 which extends to an ear 39 upon the rear portion of the shaft 35.

Upon the exterior of the casing 19 is a return receptacle 40 from which the customer may regain his coin in case the goods are exhausted. The receptacle 40 is in communication with the interior by means of a slot 41 adapted to be closed by a slide plate 42 coupled to links 43 and connected at opposite ends of the slide plate, such links 43 being in turn coupled to a pair of links 44 running to and pivoted in ears upon the shaft 35 as shown at 45.

The coin diverting plate 46 normally lies in a diagonal position as shown in Fig. 80 5 with its lower end arranged to direct the coin out through the slot 41 and into the exterior receptacle 40. This plate 46 is pivoted at 47 and carries a horizontal extension 48 beneath which engages the upwardly curved outer end of the trip arm 49 pivoted at 50 to a part of the casing and having its rearmost end 51 projecting through a slot 52 into the bottle chute 25 and into the path of the descending bottles 15. 90

In operation, the prospective purchaser, viewing the goods through the glass panels 12 and informed as to the contents of the bottles in the various compartments by the legend upon the outside of the cabinet just 95 above the glass panels, makes his selection and thereupon places a coin of the denomination called for in the opening 28 in the respective casing 19. The coin descending in the slot 29 strikes the upper end of the 100 locking lever 31 and causes its lower end 32 to swing over to the position shown in Fig. 6 where it is out of the path of the lug 34. The shaft 35 may thus be rotated by pulling outwardly upon the handle 20. This action 105 also draws the slide 22 forwardly to the position indicated in Fig. 4, allowing the bottle previously received in the slide pocket to descend through the chute 25 and into the basket 26 where it is accessible to the customer. 110

Now the coin 30 is retained at the base of the slot 29 as shown in Figs. 5 and 6 until the handle 20 is actually pulled back. The retaining finger 36 is then swung down by 115 reason of the link connection 38 with the shaft, permitting the coin to fall, the movement of the shaft 35 also acts to swing the closure plate 42 down in back of the slot 41. The coin falling upon the diverting plate 120 46 is thus prevented from sliding out through the opening 41 and into the pocket 40 where the customer could recover it. A bottle 15 as shown in Fig. 5, will in descending through the chute 25 strike the projecting end 51 of the trip arm and cause the swinging of the diverting plate about its pivot 46. This action releases the coin and allows it to drop into the bottom of the casing. However, should there be no bottle 125 130

in the compartment selected, the trip arm will not move the diverting plate 46 and as a result, on the returning of the handle 20 to the original position, the plate 42 will be lifted

5 and the coin will slide out through the opening 41 into the pocket 40 where it may be reclaimed by the customer.

The bottles will thus descend singly to the slide and be ejected in sequence. The inclined shelves will permit the bottles to roll smoothly down to the slide without breakage and at the same time be kept in a cold condition by the drip water of the ice in the compartment above. The bottles pass the 15 glass partitions 12 one above another so that they may be inspected and also the progress of the bottles down the shelves noted. The shelves will hold a great number of bottles and will require replenishing only at 20 infrequent intervals. The arrangement and disposition of the parts is such that access of outside warmer air is prevented and also the escape of the cold atmosphere is almost entirely avoided while however not interfering with the ready delivery of the goods.

I have illustrated and described a preferred and satisfactory embodiment of my invention, but it is obvious that changes may be made therein within the spirit and scope 30 thereof as defined in the appended claims.

I claim:

1. A refrigerator comprising a refrigerated cabinet containing bottled goods and having a delivery chute, a slide to control 35 the movement of bottles to the chute, means to normally lock the slide and to release same on inserting a proper coin, said means comprising a casing having a coin slot with means to unlock the slide actuated by the 40 presence of the coin, said casing having an outlet for the coin, means to hold the coin in the slot until the slide is moved, means to mask the outlet as the coin is released, means to divert the coin to the outlet, and means

actuated by the passage of a bottle through 45 the chute for shifting said diverting means out of the path of the cam, substantially as described.

2. A vending machine comprising a cabinet for the goods having a delivery chute, 50 delivery means for depositing the goods in the chute, a coin chute, a lever projecting in the coin chute and adapted to be moved by a coin, a shaft normally locked against rotation by said lever and connected to be 55 turned when the delivery means is operated, means normally in the chute for holding the coin therein and connected to said shaft for withdrawal on the turning of the shaft, a rocking diverting plate in the path of the 60 coin for returning the coin to the customer, a movable shutter normally permitting return of the coin and coupled to the shaft for movement therewith, and means projecting into the goods delivery chute for shifting 65 said plate out of the path of the coin on the passage of the goods.

3. A vending machine comprising a cabinet for goods having a delivery chute, delivery means for depositing articles in the 70 chute, a shaft connected to said delivery means and adapted to be rotated on the operation of said means, a coin chute, a lever projecting into the coin chute for movement by a coin and arranged to lock said shaft 75 against movement, a trip finger for arresting the movement of the coin in the chute connected to said shaft for withdrawal from the coin chute when the shaft is turned, a coin return receptacle, a diverting plate pivoted below the coin chute for directing the coin to the return receptacle, means in the delivery chute moved by the goods passing therethrough for shifting the plate out of the path of the coin, and means moved by 80 the shaft for cutting off the return receptacle from access to the coin.

CHARLES F. CALLAHAN.
